UNITED STATES PATENT OFFICE

2,558,989

APPARATUS FOR FEEDING SHEETS
VERTICALLY

Carl W. Spohr, Chicago, Ill., assignor to The Curtiss Candy Company, Chicago, Ill., a corporation of Illinois

Application January 24, 1946, Serial No. 643,014

9 Claims. (Cl. 271—12)

1

There have been many devices for feeding individual sheets or pieces from a pile. The most reliable, known as suction feeders, have included a suction device coming down on top of the pile and seizing one sheet to separate it from the others. These have usually operated in conjunction with pile-elevating mechanisms to keep the top of the pile at the proper level for the suction device. In the past these pile-elevating mechanisms have been quite complicated. One of the features of the present invention is the provision of a simple pile-elevating mechanism.

Another feature of the invention is the provision of a simple feeder especially desirable for use in feeding sets of bags to be filled. The bags are first turned upright and then, in proper timed relationship, are moved through a guideway into the control of the filling conveyor by the simple expedient of a blast of air.

Additional objects and advantages of the invention will be apparent from the description and from the drawings in which:

Figure 1 is a side view partly broken away of the form of the invention chosen for illustration;

Fig. 2 is a top view of the apparatus shown in Fig. 1;

Figs. 3, 4, and 5 are vertical, sectional views taken approximately on the lines 3—3, 4—4, and 5—5 respectively in Fig. 1;

Fig. 6 is a view corresponding to Fig. 5 but showing the parts in different positions;

Fig. 7 is a horizontal, sectional view of the valve mechanism taken on the line 7—7 of Fig. 5;

Fig. 8 is a longitudinal view partly in section of the suction head, the section being taken approximately on the line 8—8 of Fig. 3;

Fig. 9 is a fragmentary perspective view showing the control of eccentric 52 which returns the control switch to "off" position;

Fig. 10 is a fragmentary sectional view showing the biasing spring for the suction head which is operated against the tension of the spring by the cam.

Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

General operation

The apparatus is especially designed for feeding a piece comprising a set of 12 bags on a common backing member and the piece may, therefore, be referred to as a bag set.

2

As seen in Fig. 1, the feeding apparatus chosen for illustration lifts the top bag set from a pile 11, turns it upright, and feeds it to a conveyor unit which may include slide 12 and chains 13. To accomplish this, a suction head 14 is swung to the top of the pile as seen in Fig. 6. Suction is applied thereto by operation of valve 16. The suction head 14 is raised to the position shown in Fig. 5. A guide plate 17 is swung into place forming a channel 18 between it and the suction head 14. When valve 16 is controlled to shut off the suction and release the piece which has been raised by the suction head 14, the piece is blown by an air nozzle 19, seen best in Fig. 2, into the control of the conveyor. Proper registration of the bag set with respect to the conveyor is accomplished by blowing the bag set against a stop member 21 carried by the chain 13.

Drive

The mechanism is driven by a motor 23 which, through a gear box 24, drives a main shaft 26. As seen best in Fig. 5 the shaft 26 carries a plurality of cams 27, 28, and 29. The cam 27 operates plunger 31 of valve 16. The cam 28 operates the guide plate 17, and the cam 29 operates suction head 14. The guide plate 17 is carried by arms 32 journaled to the frame at 33 and urged toward the position shown in Fig. 5 by spring 34. The arms 32 are moved from the position shown in Fig. 5 to the position shown in Fig. 6 by the thrust of cam 28 on cam follower roller 36.

The suction head 14 is carried by arms 37 which are carried by shaft 38. The shaft 38 is biased toward the position shown in Figs. 3 and 5 by a spring similar to the spring 34. The shaft 38 and arms 37 are moved to the position shown in Fig. 6 by cam 29 acting on cam follower roller 41.

Cycle control

In the illustrated apparatus, the feeder does not operate continuously but operates in intermittent cycles, a cycle being initiated automatically at the proper time for feeding another bag set. The intermittent operation is obtained by starting and stopping motor 23. This motor is controlled by mercury switch 43 which is mounted on control shaft 44. Between cycles the mercury switch 43 is held in the off position by a latch mechanism shown in Fig. 4. When the bag set B in Fig. 4 has advanced to a predetermined point along the conveyor, a pin 46 carried by one of the chains 13 strikes latch lever 47 pivoting it and releasing latch member 48 so that it and shaft 44 are rotated by spring 49, thus tilting the mercury switch 43 to the on position. Just before the end of one revolution, a lug 51 (Fig. 5) carried by cam 28 strikes an eccentric 52 on shaft 44 and rocks the shaft 44

back to the position shown in Fig. 4 compressing the spring 49 and tilting the mercury switch 43 to the off position. The motor 23 has enough overrun so that the lug 51 rides slightly past the eccentric so as not to block its movement to the on position when the latch 48 is next released.

Air control

Shortly after the start of the cycle, cam 27 actuates pin 31 of the valve 16 thrusting valve plunger 53 to the right in Fig. 7. The first part of the movement moves the plunger 53 from the seat 54 so as to connect the hose 56 leading to the suction head 14 with the suction supply hose 57 which may be connected to any suitable suction pump. Loss of suction by flow of air through ports 58 is almost immediately prevented by further movement of the plunger 53 in which it telescopes over plug 59, the latter sealing the right-hand end of plunger 53.

After the suction head has raised a bag set to the vertical position and the guide plate 17 has been brought to its guiding position as shown in Figs. 3 and 5, the cam 27 moves to a position to release the pin 31 and plunger 53. The plunger 53 seats on seat 54 shutting off the suction from the suction head and moves away from plug 59 connecting the suction head hose 56 with the atmosphere through ports 58 and 61. The plunger 53, as well as the other operating parts, is, of course, well lubricated with oil and the oil serves as a seal.

When the suction on suction head 14 is thus relieved by connection of the suction head through hose 56 and ports 58 and 61 with atmosphere, the bag set which has been raised is released. Air constantly blowing through nozzle 19 is then effective to blow the bag toward the end into the conveyor formed in part by chains 13. Of course, the bag set tends to drop as it is blown and a guideway 63 is provided for limiting the downward movement of the bag set and guiding it onto the conveyor slide 12. The nozzle 19 may be constantly supplied with compressed air by a hose 64 which may be connected to any suitable source of compressed air supply. It may be noted that compressed air is used in other parts of the machine for which the feeder is especially intended, so that it is readily available.

From the foregoing it is seen that the bag set is separated from the pile and is fed to the conveyor in a very simple manner. In the conveyor the bags may be fed, after passing beyond the range of the blast from nozzle 19, either by the chains 13 or by being loosely gripped between belts or other moving means.

Pile elevator

As seen best in Fig. 3, the pile 11 rests on elevator platform 66. This platform is urged upwardly by counterweight 67 acting through chain 68 and rod 69. The rod 69 also serves to guide the platform 66 in its upward movement sliding smoothly in sleeve 71.

In order for the suction feeder to work properly, the top of the pile 11 should be quite close to the level at which the face of the suction head will be horizontal. According to the present invention, this is accomplished in a very simple manner. As the suction head is depressed to the position shown in Fig. 6, a shoulder 72 carried by the shaft 38, which also carries the suction head and arms 37, strikes a release rod 73 which engages a lock bar 74 and presses it toward a horizontal position. When the lock bar 74 is in

the horizontal position, a hole therein is aligned with sleeve 71 so that rod 69 may be moved upward freely by the counterweight 67. It will, therefore, raise the pile 11, as the suction head 14 is raised from the Fig. 6 position, until the rod 69 is gripped by the lock lever 74. Since the locking will be uniformly effective at a given position of the arms 37, it is evident that the top of the pile 11 may be maintained at a fairly constant level. This level may be adjusted by adjustment nut 76 on release rod 73. The weight 67 is sufficiently heavy to press the bags quite firmly against suction head 14 so that they will reliably seal the suction openings therein. Preferably, the passage to each opening is reduced so that one unsealed opening will not let in so much air that there will be insufficient suction at the other openings.

The lock lever 74 is made effective by being pivoted upwardly about pivot 77, the lock lever being urged in that direction by a spring 78, the tension of which is adjustable. This spring does not need to apply the full lock force because friction between rod 69 and lock lever 74 will increase the locking action of the lock lever 74 once the locking effect begins.

At any time the platform 69 may be pressed downwardly by hand to add more bag sets to the pile 11. The downward movement of rod 69 automatically releases the locking action of lock lever 74. The additional bag sets are supplied to the pile 11 between the cycles, or at least after the suction head 14 has raised one bag therefrom. There is plenty of time to make this simple operation without stopping the machine. The first time the suction head 14 comes down on the pile after the pile has been increased, the platform 66 is automatically adjusted to bring the top of the pile to the right level.

Suction head

Although the suction head may take a variety of forms, that illustrated in Fig. 8 is at present preferred and has some advantages of simplicity and dependability. Arms 37 carry blocks 81 and 82 to which the suction head or face plate 14 is attached. A pipe connection or nipple 83 is threaded into block 81 and to it is connected hose 56 by which suction is supplied from the valve 16. A second pipe 85 is threaded into the other side of block 81 and extends into block 82. Suction ports 84 are provided through blocks 81 and 82 and also through an intermediate block 86. It has been found that the three suction ports opening onto the face of the suction head 14 are sufficient. The pipe 85 is provided with a port 87 at a position lying within the block 86 and communicating with the suction port therein. To seal the pipe 84 to the blocks 82 and 86, packing sleeves 88 are provided and tightened into position by screws as shown.

Operation

Although the general operation was set forth at the beginning of the description, a more detailed statement thereof may be helpful in understanding the invention.

At the start of the cycle the parts are approximately in the positions shown in Figs. 1 to 5 and 7. At the proper time, when the previously fed bag-set has advanced far enough to be out of the way, a pin 46 strikes latch lever 47 releasing latch member 48 to permit spring 49 to rock shaft 44, tilting mercury switch 43, and starting the motor 23. The motor 23 drives cams

27, 28, and 29. Cams 28 almost immediately moves guide plate 17 from the Fig. 5 position to the Fig. 6 position. Cam 29 begins at about the same time to remove the suction head 14 from the Fig. 5 position to the Fig. 6 position. During this movement the cam 21 operates valve 16 to apply suction to the suction head 14.

As the suction head 14 approaches the position of Fig. 6, shoulder 72 strikes release bar 73 leveling lock lever 74 to thereby release rod 69 which is again locked as the suction head 14 begins its upward movement. This momentary release of the lock bar 74 permits the platform 66 to assume the proper position to bring the top of the pile 11 to the desired height.

As the suction head 14 is permitted to raise by cam 29 it carries a bag set with it to the position shown in Fig. 3.

Cam 28 then permits the guide plate 17 to assume the position shown in Fig. 3, forming a passage for the longitudinal movement of the bag set B. Thereafter, the cam 27 releases valve stem 31 so that valve plunger 53 shuts off the vacuum and connects the suction head 14 to atmosphere thereby releasing the bag set which had been held by the suction head. Thereupon, the constant blast of air from nozzle 19 is effective to blow the bag set between the chains 13 so that it is moved along by the conveyor closely following the preceding bag set. The proper positions of the bag sets relative to the chains are determined by their being blown against stops 21. The bags, as thus positioned or registered and while still under the influence of the air blast, may, if desired, move into the bite of friction means, such as a pair of belts.

From the foregoing it is seen that a very simple and reliable feeding mechanism has been provided in which the top of the pile is automatically maintained at the right height, the top bag set is separated from the pile, turned to a vertical plane, and advanced into a conveyor.

I claim:

1. A feeder for individually feeding vertically-disposed pieces from a pile of horizontal pieces including a suction head, means for swinging the suction head to a horizontal position to seize the top piece of a pile and to a vertical position to raise and swing the top piece to a vertical disposition, guide means and means for moving the guide means to form a passageway between it and the suction head, means for applying suction to the suction head when it is in the horizontal position and relieving said suction after said passageway has been formed, and means for blowing the piece along said passageway when the suction has been released.

2. A feeder including a suction head movable between a seizing position and a release position, effective in its movement to tilt a seized piece and effective in its release position to cooperate with other means to form a passageway, means for applying suction to the suction head when it is in the seizing position and relieving said suction when it is in the release position, and means for blowing the piece along said passageway when the suction has been released.

3. A feeder including a suction head movable between a seizing position and a release position, effective in its movement to tilt a seized piece and effective in its release position to cooperate with other means to form a passageway, means for applying suction to the suction head when it is in the seizing position and relieving said suction when it is in the release position, and

means comprising a nozzle constantly discharging a jet of air for blowing the piece along said passageway when the suction has been released.

4. A feeder including a suction head movable between a seizing position and a release position, effective in its movement to tilt a seized piece and effective in its release position to cooperate with other means to form a passageway, means for applying suction to the suction head when it is in the seizing position and relieving said suction when it is in the release position, means comprising a nozzle constantly discharging a jet of air for blowing the pieces along said passageway when the suction has been released, and a pile-elevating mechanism operated in conjunction with the suction head to position the top of the pile for co-action with the suction head.

5. A feeder including a suction head movable between a seizing position and a release position, effective in its movement to tilt a seized piece and effective in its release position to cooperate with other means to form a passageway, means for applying suction to the suction head when it is in the seizing position and relieving said suction when it is in the release position, means for blowing the piece along said passageway when the suction has been released, a motor for driving the feeder, and means for starting the motor in timed relationship to an associated device and for stopping the motor at the end of one cycle of the feeder.

6. A feeder for individually feeding pieces from a pile including a suction head, means for moving the suction head to the pile to seize the top piece of the pile and to a different position over a support, means for applying suction to the suction head when it is at the top of said pile and until it reaches the position over said support and for discontinuing the suction while the suction head is in such position to drop said piece on said support, means adapted to form a passageway for the piece on said support, and means for blowing the piece along said passageway when the suction has been released.

7. A feeder for individually feeding pieces from a pile in tandem relationship and each registered with other equipment, including a conveyor having a registration stop associated therewith, a suction head, means for moving the suction head to the pile to seize the top piece of the pile and to a different position over a support, means for applying suction to the suction head when it is at the top of said pile and until it reaches the position over said support and for discontinuing the suction while the suction head is in such position to drop said piece on said support, means adapted to form a passageway for the piece on said support, and means for blowing the piece along said passageway into control of the conveyor and against the registration stop when the suction has been released.

8. A feeder for individually feeding vertically-disposed pieces from a pile of horizontal pieces including a suction head mounted to swing about a fixed axis, means for swinging the suction head to a horizontal position to seize the top piece of a pile and for swinging it upwardly to a vertical position to raise and swing the top piece to a vertical disposition, guide means and means for moving the guide means into the path of movement of the suction head following its upward movement to a position cooperating with it in its vertical position to form a passageway for the vertically-disposed piece, means for applying suction to the suction head when it is in the

horizontal position and discontinuing the suction after said passageway has been formed, and means for moving the piece along said passageway when the suction has been released.

9. A feeder including a suction head movable about a fixed axis between a seizing position and a vertically-disposed released position, effective in its movement to tilt a seized piece and effective in its release position to cooperate with other means to form the laterally supporting guides of a passageway, means for applying suction to the suction head when it is in the seizing position and discontinuing the suction when it is in the release position, and means for moving the piece in an axial direction along said passageway when the suction has been released.
